UNITED STATES PATENT OFFICE

153,153

DESIGN FOR AN ADJUSTABLE ORNAMENTAL CHAIN

Louis Kramer, New York, N. Y.

Application July 27, 1948, Serial No. 147,796

Term of patent 3½ years

(CL. D45—16)

To all whom it may concern:

Be it known that I, Louis Kramer, a citizen of the United States of America and a resident of the city of New York, in the county of Queens and State of New York, have invented a new, original, and ornamental Design for an Adjustable Ornamental Chain, of which the following is a specification, reference being had to the accompanying drawing, forming a part thereof.

Fig. 1 is a plan view of an adjustable ornamental chain embodying my new design with the chain in position for use as a necklace;

Fig. 2 is a front view thereof, partially in perspective, with the chain in position for use as a bracelet;

Fig. 3 is a cross section taken along the line 3—3 of Fig. 2; and

Fig. 4 is a fragmentary side elevational view of the pendant element shown at the end of Fig. 1.

The dominant features of my design reside in the portions shown in full lines, the faceted elements of the flexible chain portion being repeated throughout the length of said portion as indicated by the dot and dash lines.

I claim:

The ornamental design for an adjustable ornamental chain, substantially as shown and described.

LOUIS KRAMER.
